UNITED STATES PATENT OFFICE.

FREDERICK VAN DUZER LONGACRE, OF NEW YORK, N. Y., ASSIGNOR TO
INGERSOLL-RAND COMPANY, OF NEW YORK, N. Y., A CORPORATION
OF NEW JERSEY.

UNLOADER FOR SINGLE-ACTING COMPRESSORS.

No. 834,626.

Specification of Letters Patent.

Patented Oct. 30, 1906.

Application filed November 23, 1904. Serial No. 234,011.

To all whom it may concern:

Be it known that I, FREDERICK VAN DUZER LONGACRE, a citizen of the United States, and a resident of the borough of Manhattan, in the city and State of New York, have invented new and useful Improvements in Unloaders for Single-Acting Compressors, of which the following is a specification.

The object of this invention is to provide certain improvements in the construction, form, and arrangement of the several parts of an electrically-operated unloader for compressors.

The unloader herein represented is especially adapted for unloading the discharge-valve of a one-stage compressor.

In the accompanying drawings, Figure 1 represents the unloader in vertical central section, the parts being in the position which they assume when the electromagnet is de-energized and communication is established between the pressure-port of the discharge-valve and the receiver. Fig. 2 is a similar view showing the positions of the parts when the electromagnet is energized and communication is established between the pressure-port of the discharge-valve and the exhaust-port leading to the atmosphere. Fig. 3 is a diagrammatic view showing an electrical system suitable for use in controlling the operation of the unloader-electromagnet, the said view including portions of a one - stage air - compressor, a receiver, the unloader, and the pipe connections between the discharge - valves, receiver, and unloader; and Fig. 4 is a detail view in section of one of the discharge-valves.

In this type of unloader pressure is established back of the discharge-valve by opening communication from the receiver to the back of the discharge-valve, and the discharge-valve is unloaded at any desired moment by the energization of an electromagnet which will operate a valve and open communication from the space back of the discharge-valve to the atmosphere, which valve at the same time will close the receiver pressure-port.

The electromagnet comprises a suitable bracket 1, the coil 2, and the core 3.

The electromagnet herein represented is of the solenoid type, and the core 3 is fitted to slide vertically in a tube 4, the lower end of which is provided with a removable cap 5,

which cap serves to support the core 3 when the magnet is deenergized.

The bracket 1 of the electromagnet is sur- 55 mounted by the valve-box 6, the said valve-box having a chamber 7, the upper end of which is closed by a top cap 8, which has a screw-threaded engagement with the walls of the said chamber. This top cap 8 is pro- 60 vided with a pressure-port 9, which is adapted to be connected to a receiver 22 through a pipe 23. A suitable valve-seat 10 is provided at the inner end of the port 9. A pressure- 65 port 11 opens into the valve-chamber 7 70 through the side of the valve-box, which port 11 is arranged to be connected to the space back of a discharge-valve 24 of a one-stage air-compressor 26 through a pipe 25. In the present instance two discharge-valves 24 and 75 their pipes 25 are shown as connected to the common pressure-port 11. A ring 12 is seated in the bottom of the valve-chamber 7, the bore of which ring forms an exhaust-port 13, which communicates with a central ex- 75 haust-chamber 14, from which transverse ports 15 lead to the exterior of the valve-box. The mouth of the port 13 is provided with a valve-seat 16.

The ball-valve is denoted by 17 and nor- 80 mally rests upon its seat 16, leaving communication open between the receiver pressure-port and the discharge-valve pressure-port.

The valve-box 6 is provided with a stepped hollow depending portion 18 19, the larger 85 portion 18 being fitted to the top of the bracket 1 and the smaller portion 19 being extended into the electromagnet 2 and having a screw-threaded engagement with the top of the core-tube 4.

A rod 20 rests upon the top of the core 3 and extends with an easy sliding fit upwardly through the valve-box into engagement with the bottom of the valve 17. It is desirable that the upward movement of the rod 20 and 95 core 3 when the electromagnet 2 is energized be retarded to a certain extent, so as to prevent a too rapid shifting of the valve 17. This object is accomplished by making the valve-box 6 of some magnetic material—such, 100 for instance, as magnetic iron—so that when the electromagnet 2 is energized a certain amount of magnetism is imparted to the valve-box 6. The attraction of the rod 20 to

the valve-box 6 will be sufficient to retard the upward movement of the rod 20 through the bore of the said valve-box. This retarding effect on the rod 20 will reduce the noise incident to the valve 17 striking its seat 10.

An oil-duct 21 leads vertically through the core 3 and bottom cap 5 for permitting the ready escape of any oil which may leak down along the sides of the rod 20.

10 In operation the unloader stands normally with its electromagnet deenergized and the load thrown onto the back of the discharge-valve of the compressor. When it is desired to unload the valve, the electromagnet is energized, thus raising the core 3 and rod 20, and thereby lifting the valve 17 away from its exhaust-port seat up into its receiver pressure-port seat. This movement will open communication from the discharge-valve pressure-port 11, through the exhaust-port 13, chamber 14, and transverse ports 15, to the atmosphere. Communication at the same time is cut off to the receiver through the port 9 by the valve 17.

15 By providing an upper cap 8 it will be seen that access to the valve and valve-chamber may be readily obtained by removing the said cap, also that the ring 12 may be readily renewed at any time by the removal of this upper cap.

20 In Fig. 3 I have shown in diagram an electrical system suitable for use in operating the electromagnet 2 of the unloader. This system comprises in a general way a motor 27, having a shunt-winding 28 and a series winding 29, a starting-resistance 30, a magnetic clutch 31, an automatic switch 32, its magnetic blow-out 33, a magnetic-controlled contactor 34, an air-pressure-governed electric contactor 35, a field-resistance 36, and a main-line switch 37. This electrical system forms no part of the present invention, but is shown, described, and claimed in a pending application filed by me on November 20, 1903, Serial No. 181,985.

25 What I claim is—

1. An air-compressor, a discharge-valve therefor and an unloader comprising a valve-box, its chamber having a pressure-supply port, a discharge-valve port in communication with the back of the discharge-valve, and an exhaust-port, a valve arranged to alternately open and close communication from the pressure-supply port and the exhaust-port to the discharge-valve port and electrically-controlled means for operating the valve.

2. An air-compressor, a discharge-valve therefor and an unloader comprising a valve-box, its chamber having a pressure-supply port, a discharge-valve port in communication with the back of the discharge-valve, an exhaust-port, a ball-valve arranged to alternately open and close communication from the pressure-supply port and exhaust-port to

the discharge-valve port and electrically-controlled means for operating the valve.

3. An air-compressor, a discharge-valve therefor and an unloader comprising a valve-box, its chamber having a pressure-supply port, a discharge-valve port in open communication with the back of the discharge-valve and an exhaust-port, a valve arranged to alternately open and close communication from the pressure-supply port and exhaust-port to the discharge-valve port, and an electromagnet of the solenoid type having its core arranged to control the operation of the valve as the magnet is energized or deenergized.

4. An air-compressor, a discharge-valve therefor and an unloader comprising a valve-box, its chamber having a pressure-supply port and an exhaust-port in alignment and a discharge-valve port in communication with the back of the discharge-valve, a valve arranged to alternately open and close communication from the pressure-supply port and exhaust-port to the discharge-valve port, an electromagnet of the solenoid type and a rod fitted to slide in the valve-box and interposed between the core and valve for bringing the valve under the control of the operation of the electromagnet.

5. An air-compressor, a discharge-valve therefor and an unloader comprising a magnetic valve-box, its valve-chamber having a pressure-supply port and exhaust-port in alignment and a discharge-valve port in communication with the back of the discharge-valve, a valve arranged to alternately open and close communication from the pressure-supply and exhaust ports to the discharge-valve port, an electromagnet, its core and a rod fitted to slide in the valve-box interposed between the valve and electromagnet-core for bringing the valve under the control of the operation of the electromagnet, the movement of the rod being retarded by the magnetic valve-box.

6. An air-compressor, a discharge-valve therefor and an unloader comprising an electromagnet, a valve-box, its chamber, a removable cap for closing the chamber, a pressure-supply port in the cap, an exhaust-port in alignment therewith, a discharge-valve port in open communication with the back of the discharge-valve and a valve under the control of the electromagnet for alternately opening and closing communication from the pressure-supply and exhaust ports to the discharge-valve port.

7. An air-compressor, a discharge-valve therefor and an unloader comprising an electromagnet, a valve-box, its valve-chamber, a removable cap for closing the chamber, a pressure-supply port in the cap, a removable ring having a discharge-port therein in alignment with the pressure-supply port, a discharge-valve port in open communication

with the back of the discharge-valve and a valve controlled by the electromagnet for alternately opening and closing the pressure supply and exhaust ports to the discharge-valve port.

8. An air-compressor, a discharge-valve therefor and an unloader comprising a valve-box, its chamber having a pressure-supply port, an exhaust-port and a discharge-valve port in communication with the back of the discharge-valve, a valve for opening and closing communication from the pressure supply and exhaust ports to the discharge-valve port, an electromagnet of the solenoid type having a centrally-arranged tube, a core therein, a removable bottom cap engaging the tube for limiting the downward movement of the core and a rod interposed between the top of the core and valve for bringing the valve under the control of the operation of the electromagnet.

9. An air-compressor, a discharge-valve therefor, a receiver and an unloader comprising a valve-box, its chamber having a pressure-port in communication with the receiver, a discharge-valve port in communication with the back of the discharge-valve, and an exhaust-port, a ball-valve for alternately opening and closing communication from the receiver pressure-port and exhaust-port to the discharge-valve port and electrically-controlled means for operating the valve.

In testimony that I claim the foregoing as my invention I have signed my name, in presence of two witnesses, this 14th day of November, 1904.
